UNITED STATES PATENT OFFICE

2,564,943

INSULATION SEAL FOR REFRIGERATED CABINETS

Isaac M. Wherry, Evansville, Ind., assignor to
International Harvester Company, a corpora-
tion of New Jersey

Application June 23, 1948, Serial No. 34,803

4 Claims. (Cl. 62—89)

1

This invention relates to cabinet sealing constructions, but more particularly to constructions for sealing the insulation medium disposed between the inner and outer walls of a refrigerator cabinet.

Constructions heretofore proposed for sealing the insulation between the inner and outer walls in a metal refrigerator cabinet have been directed primarily to providing a break in the heat inflow path between the low inside temperature of the cooled compartment and the higher ambient temperature outside the cabinet, and, although the necessity for maintaining the insulation in the space between the cabinet walls free from moisture has long been recognized, still no suitable construction has been provided for accomplishing this objective. Furthermore, no such construction has been proposed that is suitable for accomplishing the two-fold objective of providing an insulating break, and, at the same time, preventing the insulating material from becoming wet by breathing or from leakage of moisture into the insulating space between the walls.

It is a principal object of this invention therefore, to provide an improved seal construction for a metal refrigerator cabinet that, in addition to providing a heat conducting break between the walls, also prevents the ingress of moisture into the insulating material disposed between the inner and outer walls of the cabinet.

Another important object is to provide a simplified seal construction between the inner and outer walls of a refrigerator cabinet that is highly suitable for receiving and retaining fastening means, forced thereinto from outside the inner or outer walls, without interrupting or breaking the seal that such construction provides for preventing ingress of moisture into the insulation space between said walls.

A further object is to provide a seal construction which employs a rigid member of low heat conducting material, positioned in the space above the insulating material and between the inner and outer walls of a refrigerator cabinet, that is provided with channel-like passages in the exterior surfaces thereof which are sealed with a moisture sealing compound.

The foregoing and other objects and features of the invention will become apparent as the disclosure is more fully made, in the following detailed description of preferred embodiments of the invention, when read in conjunction with the drawings, in which:

Fig. 1 is a front sectional view of a refrigerated milk cooler cabinet in which the invention has been incorporated.

2

Fig. 2 is a section taken on line 2—2 of Fig. 1. Fig. 3 is an end sectional view of a refrigerated milk cooler cabinet in which the invention has been incorporated.

5 Fig. 4 is a section taken on line 4—4 of Fig. 3.

Fig. 5 is a top plan view—with the layer of sealing compound omitted—of a portion of a refrigerated cabinet provided with the invention.

10 Fig. 6 is an enlarged detail of a portion of the 10 end section (shown in the circle in Fig. 3) of a refrigerated cabinet to which a scuff plate has been added.

Fig. 7 is an end sectional view showing one modification of the invention.

15 Although the construction as illustrated is shown as used with a top opening refrigerated milk cooler cabinet, it should be understood that it may likewise be readily adapted for use with any type of refrigerated cabinet employing a top opening.

20 In the preferred embodiment shown a refrigerator cabinet, indicated generally by the numeral 10, comprises an outer shell 11 having vertical walls 12 and a bottom 13, and an inner shell 14 spaced from the outer shell and likewise having vertical walls 15 and a bottom 16. Cooling coils 16^a affixed to the wall of the inner shell may be connected to conventional refrigeration apparatus (not shown). Positioned in the space 25 between the outer and inner shell is the cabinet insulation 17 which may be composed of any of the conventional materials normally employed for such purposes.

25 In accordance with the teachings of this invention a rigid beam-like member 18 of low heat conducting material is adapted for positioning on top of the insulation 17 and between the inner and outer shells 14 and 11, respectively, of the cabinet. Said member 18 may be fabricated as a 30 unitary rectangular member to extend completely about the side and end walls of the inner shell 14, or it may be fabricated from separate pieces co-extensive with each respective wall and with the individual sections closely abutting one another at the corners thereof, without departing from the spirit of the invention. The embodiment illustrated indicates this member as comprising individual sections adjacent each wall, and abutting one another at the corner thereof. Although wood is preferable for this member, because of its ability to receive and retain screws or nail fastening means driven therein, it is not intended that the invention be limited to the specific use of wood for this purpose.

35 The member 18 is provided with horizontally extending channels 19 and 20 which are routed,

respectively, in the outer and inner faces of the member 18. Said channels 19 and 20 are spaced from the bottom surface 21 of the member 18, for reasons which will presently be apparent. In addition, the member 18 is also provided with a plurality of vertically extending riser channel-like passages 22 and 23, routed, respectively, on the outer and inner faces of said member. Said vertical channels extend from the top surfaces 24 and 25 respectively, of the horizontally extending channels 19 and 20, to the top surface 26 of the member 18, and are disposed at intervals spaced along the vertical outer and inner faces of the member 18. Although it is preferable, for reasons which will presently be apparent, to have the vertical riser channels 22 and 23 disposed opposite one another on the outer and inner faces of the member 18 it should be understood that this invention is not limited to a construction that utilizes that specific disposition of riser channels.

In adapting this invention to a top-opening refrigerator cabinet the outer and inner shells 11 and 14 are assembled in conventional fashion, one within the other. Next the insulated material 17 is positioned in the space between said shells and then the member 18 is positioned in tight-fitting relationship in the space between said inner and outer shells, and, at the same time, pressed against the top surface of the insulating material 17. Suitable fastening means, such as the flat-headed nails 27, may be employed to fixedly secure the member 18 placed in position between the inner and outer shells. The member 18, when so positioned, is preferably spaced slightly below the upper marginal edges of the vertical walls 12 and 15, of said outer and inner shells, and is adapted to lie in a substantially horizontal plane.

After securely positioning the member 18 a moisture sealing compound 28, of a bituminous material or a material having similar properties, is poured thereover and allowed to flow through the riser channels 22 and 23 to the horizontally extending channels 19 and 20. Upon setting, this compound effectively seals the insulation material and the space between the outer and inner shells against the entrance of moisture. Finally, a layer of the sealing compound 28 is spread over the top surface 26 of the member 18 to further seal this member against the passage of moisture therethrough and into the insulation space between the shells.

In order to improve the appearance of the exposed top surface of the inner and outer shells and the area there between, after pouring the layer of sealing compound thereover, a scuff plate 29, fashioned generally as a U-shaped channel, may be positioned to straddle the inner and outer shells, as indicated in Fig. 6. A thermal-insulating gasket-like mat 30, of rubber, or some suitable equivalent material, is inserted between the scuff plate and said outer and inner shells in order to avoid direct thermal contact between said plate and the shells. Screw fastening means 3, or the like, may be employed to retain the scuff plate securely fixed in position.

In Fig. 7 there is illustrated a modification of the specific embodiment of the vertical riser channels 22 and 23. In this modified embodiment the vertical riser channels 23^a and 22^a are angularly disposed instead of rising perpendicularly from the top surfaces of the horizontal channels 19 and 20.

It will be readily appreciated that, in addition

to providing a highly effective and simplified seal construction, this invention also offers a radically distinct advantage in that many types of fastening or securing means may be driven into the member 18, for affixment of accessories or the like to the exterior of the cabinet, without interrupting or breaking the seal construction to prevent the entrance of moisture into the insulating material or into the insulation space between the shells.

Although only preferred embodiments of the invention have been illustrated, and described in detail, it will be apparent to those skilled in the art that other modifications may be made therein without departing from the spirit of the invention or from the scope of the appended claims.

What is claimed is:

1. A refrigerator wall construction having inner and outer walls forming an insulating chamber, a heat insulating material and a cooling element within said chamber, a rigid low-heat conducting member fixedly positioned between said walls and spaced from the marginal edges thereof, said member having channel-like passages some of which are disposed horizontally and spaced from the marginal edges of said member and others vertically in opposite faces thereof with the vertical passages extending from said horizontal passages to the upper marginal edges of said member, means comprising sealing compound in said passages and on the upper surface of said rigid member and overlying said vertical passages for sealing the insulating chamber, and covering means including a low-heat conducting resilient gasket-like member positioned over the upper marginal edges of said inner and outer walls and a channel-like exterior member superposed thereover and fixedly secured to said walls.

2. A refrigerator wall construction having inner and outer walls forming an insulating chamber, a heat insulating material and a cooling element within said chamber, a rigid low-heat conducting and non-metallic member fixedly positioned between said walls and spaced from the marginal edges thereof, said member being provided with channel-like passages in the vertical faces thereof and adjacent said walls, means comprising sealing compound in said passages and a layer-like quantity of said material on the upper surface of said member that fills the space between said surface and the marginal edges of the walls for sealing the insulating chamber, and wall covering means including a low-heat conducting resilient gasket-like member positioned over the upper marginal edges of said inner and outer walls and a U-shaped exterior member superposed thereover and fixedly secured to said walls by fastening means that penetrate through said latter member and the gasket and one wall and are imbedded in said rigid member between the walls.

3. A wall sealing construction for a refrigerator of the top-opening type, comprising: inner and outer wall members spaced apart and forming an insulating chamber therebetween; the upper marginal edges of said wall members being disposed in the same horizontal plane; heat insulating material in said chamber; a rigid, non-metallic and low-heat conducting member fixedly positioned between said wall members; said member being horizontally extending and vertically spaced equi-distant from the upper marginal edge of each of said wall members and having opposite vertical faces thereof positioned in close

fitting relationship, respectively, with said inner and outer wall members; said rigid member having a plurality of channels routed in opposite vertical faces thereof with some of the channels horizontally disposed and vertically spaced from the bottom face of said member, and others vertically disposed and longitudinally spaced from one another and having the vertical channels extending from said horizontal channels to the upper face of said member; and means comprising sealing compound in said channels and a layer-like quantity of said material on the upper surface of said member and overlying said vertical channels for sealing the insulation chamber.

4. A refrigerator wall construction having inner and outer walls forming an insulating chamber, a heat insulating material and a cooling element within said chamber, a rigid low-heat conducting member fixedly positioned between said walls and spaced from the marginal edges thereof, said member having channel-like passages some of which are disposed horizontally and spaced from the marginal edges of said member and others vertically in opposite faces thereof with the vertical passages extending from said horizontal passages to the upper marginal edges of said member, means comprising sealing com-

5 pound in said passages for sealing the insulating chamber, and covering means including a low-heat conducting resilient gasket-like member positioned over the upper marginal edges of said inner and outer walls and a channel-like exterior member superposed thereover and fixedly secured to said walls.
